TANK PURGING APPARATUS

Henry Ernest Heigis, Nutley, N. J., assignor to
Specialties Development Corporation, Bloom-
field, N. J., a corporation of New Jersey

Application September 19, 1942, Serial No. 459,022

21 Claims. (Cl. 220—88)

1

The present invention relates to fuel tank purging and vapor diluting apparatus, and to a fitting adapted to be used in connection with such apparatus.

The fuel tanks of military aircraft usually are provided with one or more venting passages or openings which permit the rapid escape of fuel vapors formed in the tanks, whereby explosive vapor mixtures are minimized or eliminated which are likely to explode in the event the tanks are pierced by gun fire or the like. These venting passages normally are open, but may be closed by a valve member responsive to inertia or the surge of the fuel in the tank when a plane is catapulted into flight or is brought to a sudden stop while landing, whereby the spillage of fuel through venting passages is prevented.

It is customary to further minimize or eliminate the presence of explosive vapor mixtures in the fuel tanks while the plane is in a combat area by introducing an inert, non-combustible gas, such as carbon dioxide, which purges the vapor space or dilutes the vapor sufficiently to render them non-explosive. Where such a purging or vapor diluting medium is introduced into tanks having an inertia or surge operated valve, it has been found that the pressure of the medium operates the valve to close the venting passages. The closing of the valve causes the medium to build up a pressure in the tanks which may eventually burst the tanks, and also prevents the vapor mixtures from being removed from the tanks.

An object of the present invention is to provide a fuel tank purging and vapor diluting apparatus which overcomes the foregoing difficulties.

Another object is to provide an improved apparatus, wherein an inert medium under pressure is introduced into the vapor space of a fuel tank and the pressure of the medium is utilized for maintaining the vent passage valve in open position.

Another object is to provide an apparatus of the foregoing character which assures proper purging or vapor dilution while the plane is in flight.

Another object is to provide a simple, compact, inexpensive fitting comprising a vent, an inertia or surge operated valve for closing the vent, means for introducing an inert medium, and means for preventing the valve from closing while the medium is being introduced.

Another object is to provide a fitting of the foregoing character, wherein leakage of the fuel

2

into the purging or vapor diluting medium delivery conduit is prevented.

Another object is to provide a fitting of the foregoing character which is automatic in operation and requires a minimum amount of inspection and repair.

Another object is to provide a fitting of the foregoing character which is readily assembled and installed.

A further object consists in the construction, arrangement and operation of parts, whereby the foregoing objects are attained.

Other and further objects of the invention will be obvious upon an understanding of the illustrative embodiment about to be described, or will be indicated in the appended claims, and various advantages not referred to herein will occur to one skilled in the art upon employment of the invention in practice.

20 A preferred embodiment of the invention has been chosen for purposes of illustration and description and is shown in the accompanying drawings, forming a part of the specification, wherein:

25 Figure 1 is a diagrammatic view of an airplane having fuel tank purging or vapor diluting apparatus, illustrating an embodiment of the invention.

Figure 2 is an elevational view of a fitting utilized in connection with the apparatus shown in Figure 1.

Figure 3 is a bottom plan view of the fitting.

Figure 4 is a sectional view taken along the line 4—4 on Figure 2.

30 Figure 5 is a partial sectional view taken substantially along the line 5—5 on Figure 2.

Referring to the drawings, and more particularly to Figure 1, there is shown an airplane having a fuel tank 10 in its fuselage. Adjacent each 40 end of the tank, a fitting 11 is attached to the top wall of the tank. The fittings have an opening adapted to vent the vapor space of the tank to the atmosphere by way of a conduit 9, and have means for introducing an inert purging and vapor diluting medium, such as gaseous carbon dioxide under pressure. The fittings are each provided with a valve member 12, such as a flapper, for closing a vent opening in the fittings in response to inertia or surges of the fuel. The

50 fitting at the forward end of the tank is arranged so that the valve member or flapper 12 closes the vent opening upon a forward surge of the fuel which may occur when the plane is brought to an abrupt stop while landing; and the fitting at the rearward end of the tank is arranged so that its

flapper closes the vent opening upon a rearward surge of the fuel which may occur when the plane is catapulted into flight. The fittings are further provided with means for preventing the flapper from closing the opening while the purging or vapor diluting medium is introduced, as will be described in detail hereinafter.

The source of the purging or vapor diluting medium adapted to be supplied to the tank may be a cylinder 14 containing carbon dioxide, which is suitably located in the fuselage. The cylinder 14 is provided with a discharge control head 15 of suitable design adapted to be operated in any desired manner, for example, by a pull cable 16 having a handle 17 attached thereto and mounted on the instrument panel.

During purging or vapor dilution, it is desired that the pressure in the fuel tank does not exceed two pounds per square inch above the atmospheric pressure to which the tank is subjected. Since the pressure of the carbon dioxide in the cylinder 14 may vary between 145 and 3000 pounds per square inch, depending upon atmospheric conditions, suitable pressure regulating and reducing means are provided. Preferably, these means comprise a pair of pressure regulators 19 and 20 connected in series in a conduit 21 leading from the cylinder 14 to the fittings 11. The first regulator 19 may be adjusted to reduce the pressure at its outlet to at least 200 pounds per square inch, while the second regulator 20 may be adjusted to reduce the pressure at its outlet to about 115 pounds per square inch. As will be described hereinafter, the fittings 11 are provided with a metering orifice adapted to reduce the pressure to about two pounds per square inch.

By providing a primary and secondary regulator for regulating the pressure in two stages, more accurate regulation is attained. Sufficient carbon dioxide is supplied at all times without danger of bursting the tank due to excessive pressures.

In Figures 2, 3, 4 and 5, the fitting 11 is illustrated in detail. The fitting comprises a flange 22 adapted to be secured to the wall of the tank, and a venting body 24 and body 25 housing the flapper operating means carried by the flange (Figure 2). The venting body is substantially tubular and has a venting passage or opening 26 extending therethrough (Figure 4). The upper portion of the venting body extends above the flange 22 and is in the form of a threaded sleeve 27 adapted for connecting the venting conduit 9 thereto. The lower portion of the venting body is adapted to extend into the tank and the lower end thereof is provided with an annular lip 29, inclined slightly with respect to the horizontal, against which the flapper or valve member 12 is adapted to abut to close the venting passage 26.

As shown in Figures 2 and 4, the flapper 12 is pivotally supported by a rod or pin 30 carried by bearings 31 formed at the lower end of the venting body 24. The flapper 12 may comprise a substantially flat member having a surface adapted to abut the lip 29 to close the venting passage, and having an arm or extension 32 positioned beneath the body 25 and adapted to be engaged by the flapper operating means about to be described. The flapper 12 may be provided with a counterbalancing arm 34 adapted to facilitate actuation of the flapper in response to inertia or surge of the fuel.

In Figure 5, the body 25 housing the flapper operating means is illustrated in detail. Gen-

erally described, the body 25 houses a piston operated plunger 65 adapted to extend outwardly from the body and engage the extension 32 of the flapper to prevent it from closing the venting passage. The conduit 21 is suitably connected to the body 25 and supplies the purging or vapor diluting medium under pressure which is adapted to operate the plunger. Provision is made in the body for conducting the medium operating the plunger to an orifice 33 which meters the medium into the tank. Preferably the orifice 33 is formed in a sleeve 38, closed at one end and removably secured to the body by a threaded connection.

In order to accomplish the foregoing, the body 25 has an upper portion 35 which extends above the flange 22, and has a lower portion 36 adjacent the venting body 24 which is adapted to extend into the tank. The lower body portion is provided with a chamber 37, which is enlarged at its upper end, and which terminates in an opening 40 at its lower end. Adjacent the opening, an annular shelf 41 is provided in the chamber for supporting a flanged bushing 42 extending through the opening. A second annular shelf 44 is located at the lower end of the enlarged upper portion of the chamber 37 and a ring-shaped gasket 45 is supported, which is retained on the shelf by a cylindrical sleeve 46 fitted into the enlarged chamber portion. The sleeve 46 has an aperture 47 adapted to conduct the purging or vapor diluting medium to a passage 49 leading to the orifice 33 for delivering the medium to the tank. In order to maintain the sleeve aperture 47 in alignment with the passage 49, a set screw 50 may be threaded through the wall of the body to fit into a notch 51 or recess formed in the sleeve.

The upper end of the chamber, a ring-shaped gasket 52 is seated on a shelf 54 and on the upper end of the sleeve 46, and a flange 55 of a disc-shaped member 56 is in turn seated on the gasket 52. A gasket 57 is seated on the flange 55 and is engaged by the lower end of a chambered bushing member 59 threadedly secured in the upper portion 35 of the body 25. The upper end of the bushing member has a threaded connection for securing the conduit 21. When the bushing member 59 is threaded into position, pressure is exerted on the gaskets 45, 52 and 57 to form seals between the parts which the gaskets are interposed.

The disc-shaped member 56 has a central aperture 60 into which is inserted, at its upper end, a cylindrical strainer 61 housed in the chamber of the bushing member. This strainer prevents foreign matter such as dust or corroded metal particles from reaching the orifice 33 and causing it to become partly or completely clogged. At the lower end of the aperture 60, a downwardly facing annular valve seat 62 is provided against which a valve member, about to be described, is adapted to abut.

The means for preventing the flapper 12 from closing the venting passage, comprise the plunger 65 located in the chamber 37 of the body 25, one end of which is adapted to extend downwardly and outwardly through the opening 40 and engage the extension 32 of the flapper, and a piston 66 attached to the other end of the plunger and slidably positioned in the sleeve 46. The piston is provided with an upwardly facing valve disc 67 adapted to abut the valve seat 62 and with a downwardly facing annular seat or sealing ridge 68 adapted to engage the gasket 45.

The plunger is adapted to be normally maintained in the position shown in Figure 5 by a

cylindrical helical spring 69 telescoped about the plunger. The spring is under compression and has one end engaging the underside of the piston and has its other end seated on the flanged bushing 42, whereby the piston is urged upwardly to cause the valve disc 67 to close the opening 60. The piston and the aperture 41 in the sleeve are so related that the piston may be moved downwardly beyond the aperture 41, whereby the medium under pressure acting on the piston passes through the aperture 41 and is conducted to the orifice 33. When the piston is driven downwardly, the ridge 68 engages the gasket 45 to prevent leakage of the medium through the opening 40.

In the operation of the apparatus, the plunger 65 normally is in its retracted position, as shown in Figure 5, and the flapper is spaced slightly away from the lip 29 of the venting passage 26, as shown in Figures 2 and 4. In the event the plane is catapulted into flight, a surge of fuel toward the fitting 11 will cause the flapper to close the venting passage. During normal flight the flapper remains spaced away from the passage to allow fuel vapors to pass to the atmosphere by way of the conduit 9.

While the plunger is retracted, due to the spring 69 urging the piston upwardly, the valve disc 67 closes the opening 60, whereby the plunger and its associated parts act as a check valve for preventing fuel from getting into the purging medium conduit 21.

When the pilot enters a combat area or anticipates being attacked, he operates the vapor diluting or purging apparatus by pulling the handle 17 attached to the pull cord 16 which in turn operates to control head 15 to effect discharge of the carbon dioxide or other medium in the cylinder 14. The pressure of the medium is reduced by the two regulators 19 and 20 and flows through the conduit 21 to the fittings 11. The medium enters the bushing member 59, is filtered or strained by the strainer 61 and enters the opening 60 leading to the chamber 31. The medium is effective to unseat the valve disc 67 and to drive the piston downwardly past the aperture 41, whereby the medium flows to the orifice and is introduced into the tank. The medium is effective to dilute or displace the fuel vapors which may be formed in the space above the fuel.

The flapper 12 is prevented from closing the venting passage 26 by the plunger, which, as shown in broken lines in Figure 5, is now extended from the body 25 and engages the extension 32 of the flapper and maintains the flapper away from the venting opening, thereby permitting free passage of the fuel vapors to the conduit 9.

When it is desired to restore the system to its normal condition, the source of the purging medium is disconnected and the conduit 21 is vented to the atmosphere. This permits the spring 69 to reseat the valve disc of the piston and retract the plunger. Thereafter, if the pilot lands at a high speed and stops abruptly, a surge of fuel is again adapted to cause the flapper to close the venting passage.

While the present invention has been described in connection with an aircraft fuel tank purging or vapor diluting system by way of example, it will be understood that the principles involved can be applied to systems for other craft or vehicles where it is desired to purge or dilute fuel vapors. For example, the fuel tanks of speed

boats, armed motor vehicles and "tanks" may be protected with apparatus substantially in accordance with the invention.

From the foregoing description it will be seen that the present invention provides improved fuel vapor diluting and purging apparatus. The apparatus is readily operated, and once put into operation, functions automatically. The danger of bursting the tanks is eliminated. The fitting 10 serves as a flapper valve, a flapper valve operating means, a check valve, and a purging medium introducing means. The parts thereof are rugged in construction and can readily withstand any rough usage to which they may be subjected.

15 As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described, and all statements of the scope of the invention which, as a matter of language, might be said to fall therebetween.

I claim:

1. In an apparatus of the class described, the combination of a fuel tank having a venting passage, valve means for closing said passage in response to inertia or in response to the surge of fuel in said tank towards said passage, a source of inert medium under pressure, means for introducing the medium into said tank, and means associated with said last means and operable by the medium for preventing said valve means from closing said passage.

2. In an apparatus of the class described, the combination of a fuel tank having a venting passage, valve means for closing said passage in response to inertia or in response to the surge of fuel in said tank towards said passage, a source of inert medium under pressure, means for releasing the medium from its source, means for introducing the medium into said tank, and means associated with said last means and operable by the medium for preventing said valve means from closing said passage.

3. In an apparatus of the class described, the combination of a fuel tank having a venting passage, valve means for closing said passage in response to inertia or in response to the surge of fuel in said tank towards said passage, a source of inert medium under pressure, means for introducing the medium into said tank including pressure regulating means, and means associated with said introducing means and operable by the medium for preventing said valve means from closing said passage.

4. In an apparatus of the class described, the combination of a fuel tank having a venting passage, valve means in said tank adjacent said passage for closing said passage in response to inertia or in response to the surge of fuel in said tank towards said passage, a container of inert medium under pressure, means for releasing the medium from said container, means for introducing the medium into said tank including a two-stage pressure regulator, and means operable by the medium introduced into said tank for preventing said valve means from closing said passage.

5. A fitting for fuel tanks comprising a body having a venting passage therein, inertia respon-

sive valve means for closing said passage, said body having a second passage for introducing a medium under pressure into a fuel tank, and means adapted to be operated by the pressure medium flowing through said second passage for positioning said valve means to maintain said passage open.

6. A fitting for fuel tanks comprising a body having a venting passage therein, a pivotally mounted inertia responsive valve member for closing said passage, and means adapted to be operated by a pressure medium for positioning said valve member to maintain said passage open.

7. A fitting for fuel tanks comprising a body having a venting passage therein, an inertia responsive pivotally mounted valve member for closing said passage, and a plunger adapted to be operated by a pressure medium for positioning said valve member to maintain said passage open.

8. A fitting for fuel tanks comprising a body having a venting passage therein, a pivotally mounted inertia responsive valve member adjacent said passage for closing said passage, said valve member having an extension thereon and a counterbalancing arm, means including a passage for conducting a medium under pressure through the fitting, a piston adapted to be operated by the medium, and a plunger on said piston adapted to engage said extension and position said valve member to maintain said venting passage open.

9. A fitting for fuel tanks comprising a body means having a venting passage therein, valve means for closing said passage, said body means having a chamber provided with a pressure medium inlet and a pressure medium outlet, a piston in said chamber having a valve member for closing said inlet to shut off communication between said inlet and said outlet, and a plunger carried by said piston adapted to engage said valve means and prevent said valve means from closing said venting passage.

10. A fitting for fuel tanks comprising body means having a venting passage therein, valve means for closing said passage, said body means having a chamber provided with a pressure medium inlet and a pressure medium outlet and a passage leading from said outlet and terminating in a metering orifice, a piston in said chamber having a valve member for closing said inlet to shut off communication between said inlet and said outlet, resilient means for normally urging said piston towards said inlet, and a plunger carried by said piston adapted to extend out of said body means and engage said valve means and prevent said valve means from closing said venting passage.

11. A fitting for fuel tanks comprising a body having a venting passage therein, a flapper valve member adjacent said passage for closing said passage, said valve member having an extension thereon and a counterbalancing arm, a piston adapted to be operated by a pressure medium, and a plunger on said piston adapted to engage said extension on said valve member and position said valve member to maintain said passage open.

12. A fitting for fuel tanks comprising body means having a venting passage therein, inertia responsive valve means for closing said passage, said body means having a chamber provided with pressure medium inlet and a pressure medium outlet, a piston in said chamber having a valve member for closing said inlet to shut off communication between said inlet and said outlet,

and a plunger carried by said piston adapted to engage said valve means and prevent said valve means from closing said venting passage.

13. A fitting for fuel tanks comprising body means having a venting passage therein, inertia operated valve means for closing said passage, said body means having a chamber provided with pressure medium inlet and a pressure medium outlet and a passage leading from said outlet and terminating in a metering orifice, a piston in said chamber having a valve member for closing said inlet to shut off communication between said inlet and said outlet, resilient means for normally urging said piston towards said inlet, and a plunger carried by said piston adapted to extend out of said body and engage said valve means and prevent said valve means from closing said venting passage.

14. In a system of the class described, the combination of a fuel tank having a venting passage, a pivotally mounted valve member for closing said passage in response to inertia or in response to the surge of fuel in said tank towards said passage, a source of inert medium under pressure, means for introducing the medium into said tank, and means associated with said last means adapted to be operated by the medium for preventing said valve member from closing said passage.

15. In a system of the class described, the combination of a fuel tank having a venting passage, a pivotally mounted valve member for closing said passage in response to inertia or in response to the surge of fuel in said tank towards said passage, a source of inert medium under pressure, means for introducing the medium into said tank, and a plunger associated with said last means adapted to be operated by the medium for preventing said valve member from closing said passage.

16. In a system of the class described the combination of a fuel tank having a venting passage therein, a pivotally mounted inertia responsive valve member adjacent said passage for closing said passage in response to inertia or in response to the surge of fuel in said tank towards said passage, said valve member having an extension thereon and a counterbalancing arm, a source of inert medium under pressure, means for introducing the medium into said tank, a piston associated with said last means adapted to be operated by the medium, and a plunger on said piston adapted to engage said extension and position said valve member to maintain said venting passage open.

17. The combination of a fuel tank and a fitting attached to said tank comprising a body having a venting passage therein, valve means for closing said passage in response to inertia or in response to the surge of fuel in said tank towards said passage, said body having a chamber provided with a pressure medium inlet and a pressure medium outlet for introducing the pressure medium into said tank, a piston in said chamber having a valve member for closing said inlet to shut off communication between said inlet and said outlet, and a plunger carried by said piston adapted to engage said valve means and prevent said valve means from closing said venting passage.

18. The combination of a fuel tank and a fitting attached to said tank comprising a body having a venting passage therein, valve means for closing said passage in response to inertia or in response to the surge of fuel in said tank towards said passage, said body having a chamber

provided with a pressure medium inlet and a pressure medium outlet and a passage leading from said outlet and terminating in a metering orifice, a piston in said chamber having a valve member for closing said inlet to shut off communication between said inlet and said outlet, resilient means for normally urging said piston towards said inlet, and a plunger carried by said piston adapted to extend out of said body and engage said valve means and prevent said valve means from closing said venting passage.

19. In an apparatus of the class described, the combination of a fuel tank having a venting passage, valve means for closing said passage, a source of inert medium under pressure, means for introducing the medium into said tank, and means associated with said last means and operable by the medium to maintain said valve means from closing said passage while the medium is being introduced into said tank.

20. In an apparatus of the class described, the combination of a fuel tank having a venting pas-

sage, valve means for closing said passage, a source of inert medium under pressure, means for introducing the medium into said tank including a metering orifice, and means associated with said last means and operable by the medium to maintain said valve means from closing said passage while the medium is being introduced into said tank.

21. In a system for purging fuel supply means, the combination of liquid fuel storage means normally conditioned for venting vapors of the fuel contained in said means, fuel operated means effective for sealing said storage means to retain the fuel in said storage means, external fluid pressure operated means associated with said fuel operated means for rendering the latter ineffective for sealing said storage means, and means connecting said external means with the interior of the tank to permit purging of said storage means by the medium for operating said fluid pressure operated means.

HENRY ERNEST HEIGIS.
